UNITED STATES PATENT OFFICE.

ELROY A. CHASE, OF NORTHFIELD, VERMONT.

WHEEL FOR DRESSING STONE.

Application filed January 17, 1923. Serial No. 613,263.

To all whom it may concern:

Be it known that I, ELROY A. CHASE, a citizen of the United States, residing at Northfield, in the county of Washington 5 and State of Vermont, have invented a new and useful Wheel for Dressing Stone, of which the following is a specification.

This invention relates to a wheel for dressing stone, which is particularly adapted for use on granite or other similar material. Such material has a hard crystalline formation and the operation of dressing or rough finishing the stone is to a considerable extent a crushing operation, particularly in 10 the so-called ironing and coarse grinding operations.

It is the general object of my invention to provide an improved construction of wheel particularly adapted for producing a 15 smooth surface on such material as is above described.

With this general object in view, I have provided a wheel comprising a rotatable supporting structure and a plurality of 20 work engaging members disposed in an outwardly extended series of curved paths on the lower face of said supporting structure. These members form a composite working 25 face for the wheel and are provided with a plurality of pockets or recesses extending entirely through said members from edge to edge radially of the wheel and distinguished by the fact that the outer portion of the rear wall of each recess is projected forwardly in the direction of rotation of the 30 wheel to retard outward movement of the working material. This forward projection of the rear wall is preferably continued to a point where the edge of the rear wall extends beyond and overlaps to a greater or 35 less extent the inner face of the front wall of the recess. The pockets or recesses also 40 preferably have inclined rear faces having a wedge-like action on the working material.

Several forms of my invention are shown 45 in the drawings, in which

Fig. 1 is a partial plan view of a wheel embodying my improvements;

Fig. 2 is a sectional elevation taken along 50 the line 2—2 in Fig. 1;

Figs. 3 and 4 are an enlarged detail plan view and side elevation respectively of one of the pockets indicated in dotted lines in Fig. 1; and

55 Figs. 5 to 14 inclusive are similar views of several modified forms of pockets.

Referring to Figs. 1 to 4, I have indicated a stone dressing wheel of the general type shown in my prior application, Serial No. 563,413, filed May 24, 1922. This wheel 60 comprises a series of grinding members or rings 20 connected by radial arms 21 overlying the rings, the whole forming a rotatable structure having a driving member 22 secured thereto by bolts 23. The member 22 65 preferably has an inner flange 24 surrounding an axial feed opening 25 extending through the wheel.

A driving head 26 is mounted within the opening 25 and is preferably connected by 70 arms 27 to the flange 24. The arms 27 are inclined downwardly and rearwardly so that they exert a propeller-like action in feeding the working material downward through the opening 25 to the surface of the 75 stone. The driving head 26 is engaged by a clutch or other device (not shown) at the lower end of a suitable driving shaft and is rotated thereby.

A band 28 of steel is desirably placed 80 around the circumference of the wheel, as the remaining portion of the wheel is usually formed of cast iron and is of substantial diameter and is also rotated at a relatively rapid speed.

In the preferred construction, the rings 85 20 and arms 21 are cast as a single element to which is bolted the member 22. When the grinding rings are worn out the member 22 is removed and is used over again by bolt- 90 ing a new wheel structure thereto.

The construction thus far described is substantially as shown in my prior application and in itself forms no part of my present invention, which relates specifically to 95 certain pockets or recesses 30 formed in the working faces of the rings 20. These pockets extends entirely through the rings from edge to edge radially of the wheel and may be somewhat varied in outline as indicated 100 in the several figures of the drawings.

In the construction shown in Figs. 1 to 4, the front wall 31 of the pocket is substantially flat and extends outwardly on a forward incline, while the rear wall 32 is concave in 105 its rear portion and is provided at its outer edge with a forwardly extending portion or lip 33 which to some extent overlaps the inner edge of the front wall 31 and substantially retards outward or centrifugal movement of the wheel dressing material. The concave portion of the rear wall is also 110

downwardly inclined toward the face of the wheel so as to produce a wedge-like action upon the working material, forcing it under the wheel and materially increasing the effective action thereof.

In Figs. 5 and 6, both the front wall 34 and the rear wall 35 are substantially flat and extend outwardly at substantially the same angle, the rear wall being also inclined 10 to produce the wedge-like action above described.

In Figs. 7 and 8, the front wall 36 is inclined rearwardly instead of forwardly, while the rear wall 37 is projected forwardly 15 at its outer portion as in the construction previously described.

In Figs. 9 and 10, the construction is similar to Figs. 5 and 6, except that the front wall 38 is convex and the rear wall 39 is 20 concave, the curves of the two walls being substantially parallel.

In Figs. 11 and 12, the shape of the pockets 40 is quite similar to that shown in Figs. 9 and 10, but these pockets are formed 25 by separate blocks 41 secured by bolts 42 to to a supporting plate 43, the construction in this respect being similar to that shown in my prior application, Serial No. 477,005, filed June 13, 1921.

30 The construction shown in Figs. 13 and 14 is in a general way similar to that shown in Figs. 3 and 4, with the exception that the rear portion 42 of the rear wall is straight instead of concave and that the working faces are formed of separate blocks 43 bolted to a plate 44 as in Figs. 11 and 12.

The several forms of my invention possess 40 in common the important characteristic that the pockets extend entirely through the rings or working members and that in each case the outer portion of the rear wall is projected forwardly to retard the centrifugal or outward movement of the abrasive or other stone dressing material.

45 While I have indicated the rings 20 as being concentrically arranged, it will be understood that my improvements are equally applicable to the common scroll type of stone dressing wheel.

50 Having thus described several forms of my invention, it will be evident that other changes and modifications can be made therein by those skilled in the art within the spirit and scope of my invention as set forth in the claims and I do not wish to be otherwise limited to the details herein disclosed but what I claim is:—

1. A wheel for dressing stone having, in 60 combination, a rotatable supporting structure and a plurality of work engaging members disposed in an outwardly extended series of curved paths on the lower face of said supporting structure, said members pro-

viding a composite working face for said wheel and having a plurality of recesses 65 formed in their work engaging faces, said recesses extending entirely through said members from edge to edge radially of the wheel, and having the outer portion of the rear wall of each recess projected forwardly 70 in the direction of rotation of the wheel to a point in advance of the inner portion of the front wall of said recess.

2. A wheel for dressing stone having, in 75 combination, a rotatable supporting structure and a plurality of work engaging members disposed in an outwardly extended series of curved paths on the lower face of said supporting structure, said members providing a composite working face for said 80 wheel and having a plurality of recesses formed in their work engaging faces, said recesses extending entirely through said members from edge to edge radially of the wheel and the rear wall of each recess having a forwardly extending outer lip projected beyond and overlapping a portion of the inner front wall of the recess.

3. A wheel for dressing stone having, in 90 combination, a rotatable supporting structure and a plurality of work engaging members disposed in an outwardly extended series of curved paths on the lower face of said supporting structure, said members providing a composite working face for 95 said wheel and having a plurality of recesses formed in their work engaging faces, said recesses extending entirely through said members from edge to edge radially of the wheel and the front and rear walls of each 100 recess being respectively convex and concave and curving forwardly outwardly to form a partial closure of said recess to retard radial movement of the working material.

4. A wheel for dressing stone having, in 105 combination, a rotatable supporting structure and a plurality of work engaging members disposed in an outwardly extended series of curved paths on the lower face of said supporting structure, said members providing a composite working face for said 110 wheel and having a plurality of recesses formed in their work engaging faces, said recesses extending entirely through said members from edge to edge radially of the 115 wheel, and having the outer portion of the rear wall of each recess projected forwardly in the direction of rotation of the wheel to retard outward movement of the working material, the rear wall of said recess being 120 also rearwardly and downwardly inclined to produce a wedge-like action upon the working material.

In testimony whereof I have hereunto affixed my signature.

ELROY A. CHASE.
